US0D1021103S

(12) **United States Design Patent** (10) Patent No.: **US D1,021,103 S**
(45) Date of Patent: ** Apr. 2, 2024

(54) **CONTROLLER**

(71) Applicant: **Auris Health, Inc.**, Redwood City, CA (US)

(72) Inventors: **Kyle N. Swen**, San Carlos, CA (US); **Brett Harrison Newman**, San Francisco, CA (US); **François Pierre René Dransart**, San Francisco, CA (US)

(73) Assignee: **Auris Health, Inc.**, Redwood City, CA (US)

(**) Term: **15 Years**

(21) Appl. No.: **29/756,563**

(22) Filed: **Oct. 29, 2020**

Related U.S. Application Data

(62) Division of application No. 29/634,024, filed on Jan. 17, 2018, now Pat. No. Des. 901,018.

(51) **LOC (14) Cl.** **24-02**

(52) **U.S. Cl.**

USPC **D24/185**

(58) **Field of Classification Search**

USPC D24/185, 231, 158, 200; D21/333; D12/174; D14/401; D13/168

CPC A61B 1/0016; A61N 1/40; A61M 5/14244

See application file for complete search history.

(57) **CLAIM**

The ornamental design for a controller, as shown and described.

DESCRIPTION

FIG. 1 is a top, front, left perspective view of a controller; FIG. 2 is a top view of the controller;

FIG. 3 is a bottom view of the controller;

FIG. 4 is a left side view of the controller;

FIG. 5 is a right side view of the controller;

FIG. 6 is a front view of the controller; and,

FIG. 7 is a back view of the controller.

In the drawings, the broken lines illustrate portions of the controller, that form no part of the claimed design.

1 Claim, 6 Drawing Sheets
